(57) **ABSTRACT**

An anti-pinch electric bed includes pivotally connected first and second frames, an actuator having a first coupling portion connected with a first pivot portion of the first frame and a second coupling portion pivotally connected with a second pivot portion of the second frame. A first pivot hole of the first pivot portion or a first coupling hole of the first coupling portion is an elongated hole having a contact end. A pin inserts into the first pivot hole and the first coupling hole, and abuts against the contact end. A detect switch is disposed to the first pivot portion or the first coupling portion for sending a signal to stop the actuator or to reverse a rotation of the actuator while detecting that the pin is disengaged from the contact end. As such, the anti-pinch electric bed can prevent injury to people, other living beings, or objects.

ANTI-PINCH ELECTRIC BED

BACKGROUND OF THE INVENTION

1. Field of the Invention

The present invention relates generally to an electric bed and more particularly, to an anti-pinch electric bed.

2. Description of the Related Art

Conventional electric beds can be controlled by the user to lift the back supporting frame or leg supporting frame, and the back supporting frame or leg supporting frame can also be controlled to swing downward to return to a horizontal position. When the back supporting frame or leg supporting frame swings downward, as it gradually approaches the base frame, if children, pets, human hands, or feet accidentally enter the space between the back supporting frame (leg supporting frame) and the base frame, they may be pinched by the electric bed. If other objects, such as furniture, are mistakenly placed in the aforesaid space, the objects may be pinched or the electric bed may be damaged. Therefore, how to prevent the electric bed from pinching people, other living beings, or objects has become an urgent issue to be solved in the industry.

SUMMARY OF THE INVENTION

The present invention has been accomplished in view of the above-noted circumstances. It is an objective of the present invention to provide an anti-pinch electric bed, which can prevent injury to people, other living beings, or objects.

To attain the above and other objectives, the present invention provides an anti-pinch electric bed comprising a first frame, a second frame, an actuator, a pin, and a detect switch. The first frame includes a first pivot portion provided with a first pivot hole. The second frame is pivotally connected with the first frame and includes a second pivot portion. The actuator includes an end having a first coupling portion connected with the first pivot portion, and the other end having a second coupling portion pivotally connected with the second pivot portion. The first coupling portion has a first coupling hole corresponding to the first pivot hole. One of the first pivot hole and the first coupling hole is an elongated hole having a contact end. The actuator drives the second frame to swing relative to the first frame. The pin is inserted into the first pivot hole and the first coupling hole and abutted against the contact end of the elongated hole to connect the first coupling portion and the first pivot portion in a way that the pin is reciprocatingly moveable along the elongated hole. The detect switch is disposed to the first pivot portion or the first coupling portion to detect whether the pin is in contact with the contact end of the elongated hole. When the detect switch detects that the pin is not in contact with the contact end of the elongated hole, the detect switch sends a signal to stop the actuator or to reverse a rotation of the actuator. As a result, the anti-pinch electric bed can prevent injury to people, other living beings, or objects.

BRIEF DESCRIPTION OF THE DRAWINGS

The present invention will become more fully understood from the detailed description given herein below and the

accompanying drawings which are given by way of illustration only, and thus are not limitative of the present invention, and wherein:

FIGS. 1 to 3 are various perspective views of an anti-pinch electric bed according to a first preferred embodiment of the present invention;

FIG. 4 is a perspective view of an actuator of the anti-pinch electric bed according to the first preferred embodiment of the present invention;

FIG. 5 is a schematic view showing the anti-pinch electric bed of the first preferred embodiment of the present invention is in a state of use;

FIG. 6 is a perspective view of a part of an anti-pinch electric bed according to a second preferred embodiment of the present invention;

FIG. 7 is a schematic view showing the anti-pinch electric bed of the second preferred embodiment of the present invention is in a state of use;

FIG. 8 is a perspective view of a part of an anti-pinch electric bed according to a third preferred embodiment of the present invention; and

FIG. 9 is a schematic view showing the anti-pinch electric bed of the third preferred embodiment of the present invention is in a state of use.

DETAILED DESCRIPTION OF THE INVENTION

The structure and technical features of the present invention will be detailedly described hereunder by three embodiments and accompany drawings. As shown in FIGS. 1-4, an anti-pinch electric bed 1 provided by a first preferred embodiment of the present invention includes a first frame 10, a second frame 20, an actuator 30, a pin 38, and a detect switch 40. For illustrative purposes, the left side of FIG. 1 is referred to as the front side, and the right side is referred to as the rear side. However, this should not be construed as limiting the scope of the claims of the present application.

The first frame 10 is stationary, i.e., being fixed and immobile. It comprises a base frame 11, a front buttock supporting frame 12 disposed on the base frame 11, and a rear buttock supporting frame 18 also disposed on the base frame 11 and located behind the front buttock supporting frame 12. The front buttock supporting frame 12 includes a first framework 13, a first pivot portion 14 extending downward and forward from the first framework 13, and two first pivot holes 15 provided at the first pivot portion 14. These first pivot holes 15 are elongated holes, where the term "elongated hole" refers to a hole having a length greater than its width. Further the rear side of the elongated hole has a contact end 16.

The second frame 20 has a second framework 21 pivotally connected with the first frame 10, and a second pivot portion 22 located at a front side of the second framework 21. The second frame 20 can swing up and down relative to the first frame 10. In this embodiment, the second frame 20 serves as a back supporting frame, but in other embodiments, it can be a thigh supporting frame or a calf supporting frame.

The actuator 30 has two ends, namely an end and the other end or a front end and a rear end, provided respectively with a first coupling portion 31 connected with the first pivot portion 14, and a second coupling portion 35 pivotally connected with the second pivot portion 22. The first coupling portion 31 has two first coupling holes 32 corresponding to the two first pivot holes 15. The actuator 30 can drive the second frame to swing up and down relative to the first frame 10.

The pin 38 is inserted into the two first pivot holes 15 and the two first coupling holes 32 and abutted against the contact ends 16 of the elongated holes (i.e., the first pivot holes 15), thereby connecting the first coupling portion 31 and the first pivot portion 14 together. The cross-section of the pin 38 has a circular shape with a diameter slightly smaller than the width of the elongated holes, allowing the pin 38 to reciprocatingly move along the elongated holes (i.e., the first pivot holes 15).

The detect switch 40 is a limit switch and mounted to a place of the first pivot portion 14, which is adjacent to the contact end 16 of one of the first pivot holes 15, for detecting whether the pin 38 is in contact with the contact end 16 of the elongated hole (i.e., the first pivot hole 15). When the pin 38 abuts against the contact end 16, it also presses against the detect switch 40. When the pin 38 disengages from the contact end 16, it also disengages from the detect switch 40. In this way, as soon as the pin 38 is disengaged from the detect switch 40, the disengagement can be sensed by the detect switch 40 immediately. When the detect switch 40 senses that the pin 38 has disengaged from the contact end 16 of the first pivot hole 15, it sends a signal to a control unit 44. Since the control unit 44 is disposed to the first framework 13 and electrically connected with the detect switch 40 and the actuator 30, it can control the operation of the actuator based on the signal from the detect switch 40, causing the actuator 30 to stop or reverse its direction of rotation.

With the above disclosed structural features, as the actuator 30 gradually extends, the first coupling portion 31 drives the pin 38 to abut against the contact ends 16 of the first pivot holes 15, allowing the second frame 20 to be driven by the actuator 30 to swing upward. Conversely, as the actuator 30 gradually retracts, the second frame 20 swings downward. During this process, the weight of the second frame 20 exerts on the pin 38 through the actuator 30, such that the pin 38 will continuously abut against the contact ends 16 of the first pivot holes 15. If, at this time, children, pets, or human hands or feet are accidentally caught between the second frame 20 and the base frame 11, the second frame 20 cannot continue to swing downward. Under the continued retraction of the actuator 30, the pin 38 will move away from the contact ends 16, as shown in FIG. 5. Once the pin 38 is disengaged from the contact ends 16, the disengagement of the pin 38 will be sensed by the detect switch 40, which then sends a signal to the control unit 44 to stop actuator 30 or reverse the rotation direction of the actuator 30 (i.e., extending the actuator 30) to cause that the second frame 20 no longer swing downward or the second frame 20 starts to swing upward instead, thereby preventing injury to people, other living beings, or objects to achieve the objective of the present invention.

Based on the design of the above-mentioned structural features, various modifications to the structure of the anti-pinch electric bed 1 may be made. For example, FIG. 6 shows an anti-pinch electric bed 1a provided by a second preferred embodiment of the present invention, which has a structure similar to that of the first embodiment. The difference lies in: the first pivot hole 15a is a circular hole while the first coupling hole 32a is an elongated hole, and the contact end 33a of the first coupling hole 32a is located at the front end of the first coupling hole 32a. The detect switch 40a is located at the first coupling portion 31a and is adjacent to the contact end 33a. In this way, when the actuator 30a gradually extends, the contact end 33a of the first coupling hole 32a abuts against the pin 38a, allowing the second frame 20a to be driven by the actuator 30a to

swing upward. Conversely, as the actuator 30a gradually retracts, the second frame 20a swings downward. During this process, the weight of the second frame 20a exerts on the contact end 33a through the actuator 30a, such that the contact end 33a continuously abuts against the pin 38a. If, at this time, a child, pet, or a human hand or foot is accidentally caught between the second frame 20a and the base frame of the first frame, the second frame 20a cannot continue to swing downward. Under the continued retraction of the actuator 30a, the contact end 33a will be disengaged from the pin 38a, as shown in FIG. 7. Once the pin 38a is disengaged from the contact end 33a, the disengagement of the pin 38a will be sensed by the detect switch 40a, such that the actuator 30a can be controlled to stop or reverse its rotational direction (i.e., extending the actuator 30a), thereby preventing injury to people, other living beings, or objects so as to achieve the objective of the present invention.

Furthermore, FIG. 8 shows an anti-pinch electric bed 1b provided by a third preferred embodiment of the present invention, which has a structure similar to that of the second embodiment, except that the roles of the first frame and the second frame are swapped. Specifically, the first frame 10b, which is the back supporting frame, can be driven by the actuator 30b to swing. The second frame 20b now includes the stationary base frame, the front buttock supporting frame 12b, and the rear buttock supporting frame. The actuator 30b has a front end with a first coupling portion 31b connected with the first pivot portion 14b, and a rear end with a second coupling portion 35b pivotally connected with the second pivot portion 22b. The first coupling hole 32b is the elongated hole, and the detect switch 40b is positioned at the first coupling portion 31b adjacent to the contact end 33b. Thus, when the actuator 30b extends gradually, the contact end 33b of the first coupling hole 32b abuts against the pin 38b, causing the first frame 10b to be driven by the actuator 30b to swing upward. Conversely, when the actuator 30b retracts gradually, the first frame 10b swings downward. During this process, the weight of the first frame 10b exerts on the pin 38b through the first pivot portion 14b, such that the pin 38b continuously abuts against the contact end 33b. If, at this point, a child, pet, or human hand or foot is accidentally caught between the first frame 10b and the base frame of the second frame 20b, the first frame 10b cannot continue to swing downward. As the actuator 30b continues to retract, the contact end 33b will be disengaged from the pin 38b, as shown in FIG. 9. Once the pin 38b is disengaged from the contact end 33b, the disengagement of the pin 38b will be detected by the detect switch 40b, such that the actuator 30b can be controlled to stop or reverse the rotational direction (i.e., extending the actuator), thereby preventing injury to people, other living beings, or objects so as to achieve the objective of the present invention.

Similarly, in the third embodiment, the elongated hole and the detect switch 40b can also be arranged at the first pivot portion 14b. In this case, the first pivot hole is the elongated hole, achieving the same anti-pinch effect.

Moreover, the detect switch 40 may be of other types, such as an infrared sensor switch or a laser sensor switch, as long as it can detect whether the pin is disengaged from the contact end. If the actuator has a built-in control unit, the detect switch can also be directly electrically connected to the actuator, such that the actuator can act upon receiving the signal from the detect switch. Any such readily conceivable structural changes should be encompassed within the scope of the claims of the patent application.

What is claimed is:

1. An anti-pinch electric bed, comprising:
a first frame including a first pivot portion provided with
a first pivot hole;
a second frame pivotally connected with the first frame
and including a second pivot portion;
an actuator including an end having a first coupling
portion connected with the first pivot portion, and the
other end having a second coupling portion pivotally
connected with the second pivot portion, wherein the
first coupling portion has a first coupling hole corre-
sponding to the first pivot hole, one of the first pivot
hole and the first coupling hole is an elongated hole
having a contact end, and the actuator drives the second
frame to swing relative to the first frame;
a pin inserted into the first pivot hole and the first coupling
hole and abutted against the contact end of the elongated
hole to connect the first coupling portion and the
first pivot portion in a way that the pin is reciprocat-
ingly moveable along the elongated hole; and
a detect switch disposed to the first pivot portion or the
first coupling portion to detect whether the pin is in
contact with the contact end of the elongated hole,
wherein when the detect switch detects that the pin is
not in contact with the contact end of the elongated
hole, the detect switch sends a signal to stop the
actuator or to reverse a rotation of the actuator.

2. The anti-pinch electric bed as claimed in claim 1,
wherein the first frame is stationary and the second frame is
driven by the actuator to swing; the first pivot hole is the
elongated hole; the detect switch is disposed to the first pivot
portion.

3. The anti-pinch electric bed as claimed in claim 1,
wherein the first frame is stationary and the second frame is
driven by the actuator to swing; the first coupling hole
is the elongated hole; the detect switch is disposed to the first
coupling portion.

4. The anti-pinch electric bed as claimed in claim 1,
wherein the second frame is stationary and the first frame is
driven by the actuator to swing; the first pivot hole is the
elongated hole; the detect switch is disposed to the first pivot
portion.

5. The anti-pinch electric bed as claimed in claim 1,
wherein the second frame is stationary and the first frame is
driven by the actuator to swing; the first coupling hole
is the elongated hole; the detect switch is disposed to the first
coupling portion.

6. The anti-pinch electric bed as described in claim 1,
wherein the detect switch is a limit switch, an infrared sensor
switch, or a laser sensor switch.

7. The anti-pinch electric bed as claimed in claim 1,
wherein the detect switch is a limit switch; when the pin is
abutted against the contact end of the elongated hole, the pin
presses against the detect switch; when the pin is not in
contact with the contact end of the elongated hole, the pin is
disengaged from the detect switch.

8. The anti-pinch electric bed as claimed in claim 1,
further comprising a control unit electrically connected with
the detect switch and the actuator in a way that the control
unit receives the signal from the detect switch to control an
operation of the actuator.
